CHARLES W. MEARS AND HERMAN EISELE, OF CLEVELAND, OHIO; SAID EISELE AS
SIGNOR TO SAID MEARS

DEVICE FOR EXTINGUISHING AND HOLDING CIGARETTES

Application filed February 28, 1929. Serial No. 343,268.

This invention relates to devices for extinguishing cigarettes and for holding the same after having been so extinguished. It is the general object of the invention to provide a device of this character which is small and compact, which will retain the ashes therein, and which will materially reduce the escape of smoke and fumes.

We accomplish the foregoing objects in 10 and through the construction and arrangement of parts shown in the drawings hereof, wherein Fig. 1 represents a plan view of our holder and extinguisher; Fig. 2 a central longitudinal sectional view through the said 15 holder and extinguisher, showing the parts in closed position; Fig. 3 a view similar to Fig. 2 showing in full lines the parts in the positions assumed for receiving the lighted end of a cigarette and showing in dotted 20 lines the position of the upper member of the device after the insertion of such cigarette end; Fig. 4 an end elevation of the said holder and extinguisher; Fig. 5 a plan view of the lower member and Fig. 6 a plan view 25 of the upper member of our holder and extinguisher; and Fig. 7 a detail in perspective of one of the springs forming part of the complete device.

Describing by reference characters the 30 various parts illustrated in the drawings, A denotes generally the upper member and B the lower member of the device, both members being made preferably of sheet metal. The upper member A consists generally of 35 an extended jaw 1 having formed integral therewith a handle 2, the jaw and handle being connected by an integral concavo-convex rib 3 having notches 4 extending thereto from opposite sides thereof. It will be 40 noted that the upper faces of the jaw 1 and handle 2 form an angle with each other of less than 180 degrees.

The lower member comprises a jaw 5 and a handle 6 also connected by an integral concavo-convex rib 7, similar to the concavo-convex rib 3 of the upper member and provided with notches 8 projecting thereinto from opposite sides thereof and adapted and arranged to register with the notches 4. The 50 lower faces of the jaw 5 and handle 6 form

an angle of less than 180 degrees with each other whereby, when the jaws 1 and 5 are in engagement with each other, as shown in Fig. 2, the handles 2 and 6 diverge so that, by pressing them toward each other, the 55 jaws may be given the desired amount of opening.

It will be noted that one of the jaws (in this case the lower jaw 5) is provided with vertically extending side flanges 9 which are 60 adapted to receive the side edges of the other jaw therewithin.

In order to connect the members A and B, we employ two short cylindrical springs 10, each spring being slotted for its full length, 65 as indicated at 11 and each spring also having a notch 12 arranged nearly opposite the slit 11 and extending laterally inwardly from one edge thereof.

In assembling the parts of the device, the 70 upper and lower members are superposed, with their concavo-convex ribs in rocking engagement, and the springs 10 are then applied to the opposite sides of such ribs by opening each spring so as to clear the appropriate side flange 9 and at the same time sliding it inwardly along the ribs 3 and 7, with the slot 11 in line with the slots 4 and 8, thereby to receive therein the portions of the 75 ribs within and immediately adjacent to 80 such slots. The slots 12 are of such depth that, when the springs 10 have been moved the full distance inwardly, the outer edges of the springs will come within the flanges 9, 85 which will serve to retain the springs in place.

With the parts constructed and arranged as described, it will be apparent that, when so assembled, the springs 10 will normally hold the jaws 1 and 5 in contact, with the handles 2 and 6 spread apart. When it is desired to insert the lighted end of a cigarette 13 between the jaws, the operator presses the handles 2 and 6 toward each other, and the members A and B rock upon the concavo-convex ribs 3 and 7, which operate as a hinge. 90 When opened a sufficient distance, the lighted end of the cigarette is inserted, as indicated in Fig. 3, after which the operator releases his grasp upon the handles 2 and 6, and the 95 100

upper member assumes the position shown in the dotted lines.

When the lighted end of the cigarette is so grasped, it is quickly extinguished, and the 5 ashes 14 are collected in the space provided between the jaws 1 and 5 and the flanges 9. Furthermore, by virtue of the fact that the jaws and flanges form a substantially closed receptacle, the escape of smoke and odors 10 will be largely prevented.

The device disclosed herein is extremely simple and compact, and performs in an efficient manner the purposes for which it is designed.

Having thus described our invention, what 15 we claim is:

1. A device of the character described comprising in combination a pair of members each having a jaw and a handle projecting therefrom, the said members being mounted 20 in rocking engagement intermediate their ends, and cylindrical springs each having a slit extending the full length thereof and adapted to receive the side portions of both 25 jaws therein, each of said springs being received within slots provided in the sides of the rocking portions of said members, one of said members having side flanges thereon.

2. A device of the character described comprising in combination a pair of members each having a jaw and a handle projecting therefrom, the said members being arranged to rock one upon the other to open and close the jaws, the said device having side flanges 35 cooperating with the said jaws to provide a chamber with the bodies of said jaws for the reception of the burning end of a cigarette, and a cylindrical spring mounted on each side of the said members and each having a slit extending the full length thereof for the 40 reception of the said jaws, the outer side edges of the said springs being located within the chamber or space provided by and between the said flanges.

3. A device of the character described comprising in combination a pair of members each having a jaw and a handle projecting therefrom, each of said members having a concavo-convex rib projecting therefrom and 45 providing means whereby a rocking connection is effected between said members, one of said jaws having side flanges forming with the bodies of the jaws a compartment for the reception of the lighted end of a cigarette, and a pair of cylindrical springs each having 50 a slit extending the full length thereof for the reception of both jaws and each being received within slots extending inwardly from opposite sides of the said ribs, the outer edges of the said springs being located within the compartment or space formed by and 55 between the jaws and flanges.

4. A device of the character described comprising in combination a pair of members 60 each having a jaw and a handle projecting

therefrom, the said members being mounted in rocking engagement intermediate their ends, the said device having side flanges forming with the bodies of the jaws a compartment for the reception of the lighted end of a cigarette, and a pair of cylindrical 70 springs each having a slit extending the full length thereof for the reception of both jaws and each being received within slots extending inwardly from opposite sides of the said members, the outer edges of the said springs being located within the compartment formed by and between the jaws and flanges.

In testimony whereof, we hereunto affix 75 our signatures.

CHARLES W. MEARS.
HERMAN EISELE.
